UNITED STATES PATENT OFFICE.

CLAUDE C. GOULD, OF BATAVIA, ASSIGNOR TO THE EASTERN ELECTRICAL MANUFACTURING COMPANY, OF WHEATFIELD, NEW YORK.

TELEPHONE SWITCH SYSTEM.

SPECIFICATION forming part of Letters Patent No. 409,574, dated August 20, 1889.

Application filed March 12, 1887. Serial No. 230,616. (No model.)

To all whom it may concern:

Be it known that I, CLAUDE C. GOULD, of Batavia, in the county of Genesee and State of New York, have invented new and useful 5 Improvements in Telephone Switch Systems, of which the following is a specification.

This invention relates to a switch-board system in which each main or subscriber's line is provided in the central office with a 10 movable terminal which is automatically moved out of its normal position so as to break the connection with the ground upon sending a current through the line. Switch-board systems of this kind are described and shown 15 in Letters Patent of the United States, Nos. 355,928 and 355,929, granted to C. C. Gould and W. Smith, on the 11th day of January, 1887.

The object of this invention is to facilitate 20 and expedite the operation of connecting different subscribers; and my invention consists of the improvements which will be hereinafter fully described, and pointed out in the claims.

In the accompanying drawings, consisting 25 of two sheets, Figure 1 is a vertical section of my improved switch. Fig. 2 is a side elevation of the pivoted frame forming part of the switch. Fig. 3 is a sectional elevation of the upper part of the pivoted frame on an enlarged scale. Fig. 4 is a horizontal section in line x x , Fig. 3. Fig. 5 is a horizontal section of one of the out-sockets. Fig. 6 is a cross-section of one of the out-sockets. Fig. 7 is an edge view of one of the plugs. Fig. 8 is a 30 cross-section of the same. Fig. 9 is a diagram of two sectional switch-boards provided with my improvements. Fig. 10 is a vertical section of one of the out-sockets on an enlarged scale. Fig. 11 is a side elevation of the 35 ground-lever and connecting parts. Fig. 12 is a rear elevation of the upper portion of the vertical shifting-bar.

Like letters of reference refer to like parts in the several figures.

40 A represents the upright portion, and A' the horizontal portion, of a telephone switch-board.

a represents the supporting-frame of the annunciator secured to the upright portion A 45 of the switch-board and carrying the coils a' and the armature-lever a².

a³ represents the drop or apron, and a⁴ the horizontal locking-bolt, which is moved rearwardly when the apron drops by the tail a⁵ of the apron striking the front end of the locking-bolt.

B represents the upright shifting-bar arranged on the rear side of the upright portion A of the switch-board, and provided with vertical slots b, by which the bar is 6c guided in its vertical movements on studs or screws b', which are attached to brackets b², secured to the switch-board. The slots b limit the vertical movement of the bar B on the studs b'.

c represents a shoulder formed in the rear side of the shifting-bar B, near the upper end thereof, and engaging with a projection c', formed on the rear end of the locking-bolt a⁴, whereby the upright shifting-bar B is held in an elevated position. When the locking-bolt a⁴ is moved backwardly by the apron, the projection c' releases the upright shifting-bar B and allows the latter to drop. The downward movement of the bar B is accelerated by a 75 spring c². The upper end of the upright shifting-bar B is beveled or inclined, as shown at c³, so as to move the locking-bolt a⁴ backwardly when the upright bar is raised. The locking-bolt a⁴ is returned to its forward position by a spring c⁴.

D represents the subscriber's telephone; d, the ground-wire thereof; d', the wire running from the telephone D to a contact-point d², secured to the upright portion of the switch-board; d³, the wire running from the contact-point d² to the armature-coils; d⁴, the wire running from the armature-coils to a contact-point d⁵, secured to the switch-board below the contact-point d².

d⁶ is a contact-bow secured to the side of the upright shifting-bar B, and bearing in the upper position of the bar against the upper contact-point d² and in the lower position of the bar against the lower contact-point d⁵.

E represents a hollow frame or case, which is supported on the horizontal portion A' of the switch-board by horizontal pivots e, on which the frame E can be tilted. The frame is held in an upright position by a spring e', which is secured to the switch-board, and which bears against the rear side of the frame.

The lower end of the frame E projects downwardly through an elongated opening e^2 in the switch-board.

f represents a contact-point projecting rearwardly from the lower end of the frame E, and secured to the latter by an upright shank or bolt f' .

G represents the ground-lever, which is pivoted to the under side of the switch-board by a hanger g , and connected at its rear end to the lower end of the upright shifting-bar B. The lever G is made of wood or other non-conducting material and provided at its front end with a contact-bow g' , which straddles the contact-point f , and is provided with a ground-wire g^2 .

h represents a wire running from the contact-point d^5 to a horizontal contact-spring h' , secured in the upper portion of the frame E.

h^2 represents a horizontal contact-spring, which is also secured in the upper portion of the frame E opposite the contact-spring h' .

$h^3 h^4$ represent two depending stationary contact-points secured to the top plate of the frame E, and against which the free inner ends of the contact-springs $h' h^2$ bear in their normal position, as represented in Fig. 3. The contact-points $h^3 h^4$ are connected by a wire h^5 .

h^6 is a non-conducting push-button, which is mounted in the top plate of the frame E, and which bears upon the free ends of the contact-springs $h' h^2$.

$i i'$ represent two contact-points arranged in the frame E, respectively, below the contact-springs $h' h^2$, so that upon depressing the push-button h^6 the contact-springs $h' h^2$ can be separated from the contact-points $h^3 h^4$ and be connected with the contact-points $i i'$. The latter are connected with the operator's listening-telephone I by wires $i^2 i^3$. The contact-spring h^2 is connected with the shank of the contact-point f by a wire i^4 .

J represents a metallic case or socket secured to the outer side of the frame E, made open at its top and connected with the contact-spring h^2 .

K represents a vertical contact-lever pivoted in the frame E in rear of the socket J, which latter is provided on its rear wall with two openings $j j'$, through which the upper and lower arms $k k'$ of the lever K play. The lever K is held by a spring k^2 in a position in which one of its arms projects into the socket J, said spring being connected with the lever in front of the pivot k^2 thereof, as clearly shown in Figs. 3 and 4. The upper arm k of the lever K is made of non-conducting material and the lower arm k' is made of conducting material. The lower arm k' is connected with a power-generator L by a wire l . The lever K is provided with a stop k^4 , which limits the forward movement of its lower arm.

M represents a plug, which is connected with the main wire h by a wire m , spiral spring m' , and cord m^2 . The latter is wound upon a spool m^3 , in which the spiral spring m' is arranged so as to wind the cord upon

the spool when the cord is released. The spool rotates upon an arbor m^4 . The end of the plug M is beveled, so that upon inserting the plug into the socket J the plug, coming in contact with the lower arm k' of the lever K, forces the lower arm backwardly until the point at which the spring k^2 is attached to the lever K has passed the dead-center, when the spring continues to turn the lever K on its pivot, thereby separating the lower arm k' from the plug and holding the lever in the position represented in Fig. 3. In this position of the lever the upper arm k projects into a notch m^5 formed in the plug. The socket J is provided with a clamping-spring n , which is deflected upon inserting the plug and which holds the plug in position in the socket. The plug may also be provided with a nose or projection n' , which enters a notch n^2 in the rear wall of the socket J, for more securely holding the plug in place.

Each subscriber's line is provided at the central office with one of the frames E and its appurtenances and with a plug M. Connection is made with a called line on the same switch-board by inserting the plug M of the calling-line into the socket J of the called line.

O represents a horizontal metallic socket secured in the upright portion A of the switch-board and forming an outpoint, which is connected by a wire o with the vertical shifting-rod B of the same subscriber's annunciator located on a different switch-board, as indicated in Fig. 1. Each switch-board is provided with as many outpoints O as there are subscribers connected with the other switch-boards or sections in the same exchange.

$o' o^2$ represent two contact-springs arranged side by side in the front portion of the socket O, and secured with their bent front ends to the front side of the switch-board.

$o^3 o^4$ are wires connecting the springs $o' o^2$ with the operator's listening-telephone I by means of the wires $i^2 i^3$. The contact-spring o' is provided on its outer side with a non-conducting projection o^6 , which prevents the spring from coming in contact with the socket O, and the side of the latter is provided with an opening o^7 for the same purpose.

P represents a contact-lever pivoted to the upper side of the socket O, so as to swing in a vertical plane, and having its front arm p constructed of non-conducting material and its rear arm p' of conducting material. The lever P is pivoted to the socket O by a non-conducting support p^2 , which prevents contact of the lever with the socket. The top plate of the socket O is provided with an opening through which the arms of the lever project into the socket. The conducting-arm p' of the lever P is connected with the power-generator L by a wire p^3 . The lever P is held in position with one of its arms projecting into the socket O by a flat spring p^4 , bearing upon a non-conducting projection p^5 of the lever. The movement of the lever P is limited

in one direction by the end of the spring p^4 and in the other direction by a stop p^6 , formed on said spring.

The plug M is provided on one side with a 5 conducting projection q and on its opposite side with a non-conducting projection q' , as represented in Figs. 7 and 8, so that upon inserting the front portion of the plug into the socket O the conducting projection q will make a contact 10 with the spring o' , while the non-conducting projection q' will press against the spring o' and force the latter into contact with the socket O. By this means the operator's telephone is looped into the line with which the 15 socket O is connected. By pushing the plug farther into the socket O the front end of the plug strikes against the rear arm p' of the lever P, thereby connecting the generator L with the line o , with which the socket O is 20 connected, which causes the ringing of the call-bells on the called line o and the calling-line with which the plug M is connected. The socket O is provided with a clamping-spring r , whereby the plug is held in the 25 socket, and, if desired, the latter may be provided with a notch r' , in which the nose n' of the plug engages for the purpose of holding the plug more securely in place.

s represents a push-button attached to the 30 frame E, and connected with the generator L by a wire s' , the contact-lever K, and wire l . The push-button s is arranged in rear of the contact-spring l' , so that upon pressing the button forwardly the generator is connected 35 with the line of which said contact-spring forms part, thus enabling the operator to ring up the subscriber.

When a subscriber calls the central office, the annunciator-apron a^3 of the subscriber's 40 line drops and shifts the locking-bolt a^4 , thereby releasing the upright bar B, which latter descends and shifts the ground-lever G so as to break the contact between the bow g' and the point f , whereby the ground-connection 45 is automatically broken and held open at the central office, as represented in Fig. 11. This enables the calling subscriber to determine whether his call has been received. The operator now swings the upper end of the pivoted frame E backwardly, whereby the contact-point f is swung downwardly. This 50 brings the point f in contact with the lower prong of the bow g' , whereby the ground-connection is restored, and depresses the front 55 end of the lever G, whereby the bar B is returned to its elevated position. The operator now releases the frame E, which is returned to its vertical position by the spring e . The operator next loops in the listening-telephone 60 by pressing upon the push-button h^6 , and ascertains which subscriber is to be called. If a subscriber is wanted whose line is connected with the same switch board or section, the operator inserts the plug M of the calling-line into the socket J of the called line. During 65 the first portion of the inward movement of the plug the latter comes in contact with

the lever K of the called line and places the generator in communication with both the calling and called lines. This causes the bells 70 of both lines to ring simultaneously and automatically opens the ground-connections g^2 of both subscribers by dropping the shifting-bars B of both annunciators. The continued inward movement of the plug causes 75 the lever K to be shifted to the position shown in Fig. 3, thereby disconnecting the lever from the plug. The called line is now connected with the calling line through the plug M, socket J, contact-spring h^2 , contact-point h^4 , wire h^5 , contact-point h' , contact-spring h' , wire h , contact-point d^5 , to and through the annunciator, contact-point d^2 to the subscriber's instrument. Upon withdrawing the plug M from the socket J the shoulder m^6 at 85 the outer end of the notch m^5 strikes against the upper arm k of the lever, and shifts the latter so as to throw the lower arm k' forwardly, as represented in Fig. 1, thereby making the lever ready for the next insertion of 90 the plug.

If a subscriber is wanted whose out-point-socket O is connected with the switch-board, the operator inserts the front portion of the plug M of the calling line into the socket O 95 of the called line, whereby the operator's listening-telephone is looped into the called line. If the operator finds that the called line is engaged, the plug is withdrawn without interference with the called line. If the operator finds the called line to be disengaged, the plug is fully inserted into the socket O. The inward movement of the plug brings the latter in contact with the contact-lever P, whereby the generator is connected with both 105 the called and calling lines, and the bells of both lines are rung simultaneously. This causes the ground-connections of both lines to be opened automatically, as above described. The final inward movement of the 110 plug causes the lever P to be shifted so as to disconnect it from the plug, in the same manner in which the lever K is disconnected from the plug. The called line is now connected with the calling line, through the wire o , the 115 socket O, the plug M, and the conducting parts connected with the plug. Upon withdrawing the plug from the socket O the shoulder m^6 of the plug shifts the lever P in the same manner in which the lever K is shifted. 120

I claim as my invention—

1. The combination, with the main line and a movable plug M, connected therewith, of a socket O, also connected with the main line, a contact-lever P, connected with the generator and provided with a conducting-arm p' and a non-conducting arm p , and a spring, whereby one of said arms is projected into the socket upon inserting the plug into the socket and a connection made between the 125 main line and the generator, substantially as set forth.

2. The combination, with the main line and the frame E, of a socket J, attached to the

- frame E, a contact-lever K, projecting into the socket and connected with a generator L, and a plug M, connected with the main line, substantially as set forth.
5. 3. The combination, with the frame E and contact-lever K, of the socket J, provided with a clamping-spring n , and a plug M, connected with the main line, substantially as set forth.
4. The combination, with the frame E, the 10 socket J, and the contact-lever K, of the contact-springs h' h^2 , connected contact-points h^3 h^4 , push-button h^6 , contact-points i i' , and a listening-telephone I, connected with the contact-points i i' , substantially as set forth.
15. 5. The combination, with the frame E, of a contact-lever K, having a conducting-arm k' , connecting with the generator, and a non-conducting arm k , of a socket J and a plug M, provided with a shoulder m^6 , substantially 20 as set forth.
25. 6. The combination, with the plug M and its socket O, each connected with the main line, of a pivoted contact-lever P, connected with the generator and provided with contact-arms p p' , and a spring p^4 , whereby the contact-lever is held with one of said arms in contact with the plug, substantially as set forth.
7. The combination, with the ground-lever G, having a contact-bow g' , of the pivoted 30 frame E, provided with a contact-point f , projecting between the prongs of the contact-bow g' , substantially as set forth.
8. The combination, with an out-socket O, 35 connected with the main line, of two contact-springs o' o^2 , connected with the listening-telephone, one of said springs being insulated from the socket, and a plug M, adapted to be inserted between said springs and provided with a non-conducting portion q' , substantially 40 as forth.
9. The combination, with an out-socket O, 45 connected with the main line, of two contact-springs o' o^2 , connected with the listening-telephone and arranged in the front portion of the socket, and a contact-lever P, connected with the generator and projecting into the rear portion of the socket, substantially as set forth.

Witness my hand this 27th day of January, 50
1887.
